(57) **CLAIM**

The ornamental design for a refrigerator organizer bin, as shown and described.

DESCRIPTION

FIG. 1 is a top perspective view of the refrigerator organizer bin showing my new design.

FIG. 2 is a front view of the refrigerator organizer bin.

FIG. 3 is a rear view of the refrigerator organizer bin.

FIG. 4 is a left side view of the refrigerator organizer bin.

FIG. 5 is a right side view of the refrigerator organizer bin.

FIG. 6 is a top view of the refrigerator organizer bin.

FIG. 7 is a bottom view of the refrigerator organizer bin.

FIG. 8 is a bottom perspective view of the refrigerator organizer bin.

FIG. 9 is an enlarged detailed view of encircled area 9 in FIG. 1; and,

FIG. 10 is an enlarged detailed view of encircled area 10 in FIG. 1.

Any shading and cross-hatching are not features of the design but are utilized to illustrate the surface contours of the refrigerator organizer bin design in the drawings.

1 Claim, 10 Drawing Sheets(56)
